US00D757836S

(12) **United States Design Patent**
Miyazaki

(10) **Patent No.:** US D757,836 S
(45) **Date of Patent:** ** May 31, 2016

(54) **VIDEO CAMERA**

(75) Inventor: **Takeshi Miyazaki**, Tokyo (JP)

(73) Assignee: **Sony Corporation**, Tokyo (JP)

(**) Term: **14 Years**

(21) Appl. No.: **29/421,438**

(22) Filed: **Jul. 27, 2012**

(51) **LOC (10) Cl.** 16-05

(52) **U.S. Cl.**

USPC **D16/219**

(58) **Field of Classification Search**

USPC D16/200, 202–208, 218, 219;
348/373–376; 396/535, 539–541

(57) **CLAIM**

The ornamental design for a video camera, as shown and described.

DESCRIPTION

FIG. 1 is a perspective view of a first embodiment of a video camera showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view of a second embodiment showing my new design;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The broken lines depict portions of a video camera in which the design is embodied and form no part of the claimed design. The dot-dash lines denote the boundary of the claim and form no part of the claimed design.

1 Claim, 10 Drawing Sheets
